PROCESS FOR MAKING WOOD JOINTS

Frederick C. Valiton, South Ashburnham, Mass.

Application May 17, 1940, Serial No. 335,832

1 Claim. (Cl. 144—309)

This invention relates to the art of making wood tenon joints as applied to chairs and other articles of furniture.

Objects of the invention include the provision of an improved tenon joint for furniture, such as for the legs, backs, and rungs of chairs and other articles, in which the joint connection is made so as to greatly increase the rigidity of the article and life of the joint; the provision of means in the tenon for the reception and passage of glue to insure the spread and flow of the same; and the provision of such means having a criss-cross pattern on a compressed tenon, whereby peripheral and longitudinal threads of glue are formed to more securely hold the tenon, and longitudinal 10 passages are arranged to allow escape of the glue from the bottom of a hole into which the tenon is inserted, while the compressed material expands under its own resilience and due to the liquidity of the glue, to form an extremely tight, 15 firmly secured joint.

Other objects and advantages of the invention will appear hereinafter.

Reference is to be had to the accompanying drawing, in which

Fig. 1 is a view in elevation of one form of joint to which this invention pertains;

Fig. 2 is a section of the improved joint;

Figs. 3 and 4 are elevations of an end of turned stock from which the improved tenon is to be made;

Fig. 5 shows the end of the stock after compression;

Fig. 6 is an elevation of the completed tenon;

Fig. 7 is a plan view of the tenon, looking in the direction of arrow 7 in Fig. 6; and

Fig. 8 shows the new tenon joint used in connection with a chair back post.

As an illustration of the present invention, the numeral 10 may represent a chair leg which is to have an end inserted in a mortice 12 in the underside of a chair seat or other object 14, so as to form a support. Obviously, however, the invention is contemplated to include any similar joint in various relations wherein such joints can be conveniently utilized. The mortice 12 may be plain and conventional, and one of the advantages of the invention is that the improved holding action of the joint does not depend on any changes in the mortice or in its walls.

Turning to Figs. 3 to 7, it will be seen that to make the tenon joint of the present invention, a turned member 16 is first provided, and this member may taper as shown, if desired. The small end of the member 16 is then evenly turned

down as at 18 to a diameter slightly larger than the size of the mortice into which it is to be inserted, and radial pressure is applied to this turned portion to compress it to a diameter such that the turned end of the member could just be forced into the mortice 12. This compression operation is represented in Fig. 5 by the arrows and the grain structure at 19.

Next, the spaced longitudinal grooves 20 are cut into the compressed area, the grooves extending only from end face 22 to the abutment shoulder 24, the latter acting as a stop for the insertion of the tenon into mortice 12, as shown in Fig. 2. Then the spaced peripheral indentations 26 are cut or pressed into the areas containing the longitudinal grooves, and these indentations are made deeper than the grooves, as shown. Incidentally, it is possible to cut grooves 20 and indentations 26 prior to the compressing step, and in any case it is better to insert the tenon into the mortice soon after the compression. This time element is not essential, since it takes a long interval for the material to expand to approach its original diameter, and in fact in most cases the expansion will never be as great as the original compression, in the absence of absorption of a liquid to swell the fibers. However, the sooner the compressed end 18 is inserted in its mortice, the easier it is to force it.

The tenon having been made, glue is applied as usual to the face 22 and the tenon is forced into its mortice 12. In the absence of grooves 22, the glue will merely remain in the bottom of the closed mortice, and will not run up the sides of the tenon, as the fit is made too tight to allow such action. Hence the only holding area of the glue will be on face 22, and the more the leg 16 is forced towards the seat 14, the more pressure is exerted on the glue which in some cases has been known to force a fracture in the reduced portion 30 at the bottom of the mortice.

However, the tenon having been provided with the grooves 22, the pressure on the glue at the bottom of the mortice will cause it to be forced along the grooves outwardly, and in its passage, the glue will sink into the deeper indentations 26 and fill the same. When the first indentation has been filled, the glue will naturally follow again along grooves 22 until it comes to the second indentation and fill that one. Finally, the glue will flow out of the grooves at the shoulder 24, and the excess may be wiped or cut away.

It will be seen that the indentations 26 will mold or form threads of glue about the periphery of the tenon, and the grooves 22 will form longi-

tudinal threads, and this, in conjunction with the expansion of the tenon, due to natural resilience of the wood, and also to the absorption of the liquid glue, will form an extremely strong and long-lasting joint, having a criss-cross pattern of compressed glue-holding areas. The peripheral threads of glue will always be formed, due to the fact that the indentations 26 are deeper than grooves 22, and the glue naturally therefore flows into them.

Even in cases where a hole is bored to form a mortice thru the seat member 14, as in back posts, as illustrated at 32 in Fig. 8, the criss-cross pattern allows for the spread of the glue, and the expansion of the compressed member 15 will force the resultant threads of glue into very close contact with the walls of the mortice.

In the conventional tenon joint, it cannot be insured that the glue will contact the side walls of the tenon or mortice, and if the tenon is made small enough to force the glue backwards, the joint will soon dry out and the glue will crack and become loose, thus losing the holding power of the glue. The present invention provides for a very tight joint which still has a positive glued area, and which can be assembled with no more trouble or expense than the conventional joint,

it only being necessary to compress and cut the tenon beforehand as described.

Having thus described my invention and the advantages thereof, I do not wish to be limited to the details herein disclosed, otherwise than as set forth in the claim, but what I claim is:

The process for making a joint between wooden members which comprises forming a straight sided mortice in one member and a tenon of a size slightly larger than the mortice in the other member, compressing the tenon to substantially the size and shape of the mortice and grooving it in the compressed area leaving lands between the grooves, and swelling said tenon in said mortice to form a tight joint between the straight sides of the mortice and the lands of the tenon by applying liquid glue to the tenon prior to insertion thereof in the mortice, said glue filling the grooves; and forcing the tenon with glue applied into the mortice, said swelling having the effect of forcing some of the glue into the wood of both tenon and mortice but principally into the latter due to the compressed nature of the tenon, the tendency of the tenon to return to its original size also aiding in the swelling action.

FREDERICK C. VALITON.
